MOLD FOR HEAD CORES

Application filed March 6, 1928. Serial No. 259,517.

This invention is an improvement in molds for head cores, and more particularly in a mold for making head cores of the character shown and described in application Serial 5 No. 205,238, filed July 12, 1927.

The head core which the improved mold is designed to make has a design matrix so positioned on the core that the design will be reproduced on the casting at the bell end, 10 that is, in a position where it will be prominently displayed, even when the pipe is piled.

Pipes of the character in question are cast in rotary molds, with an independent head core, which is utilized in the formation of the bell or socket end. The core, usually composed of oil and sand molded to shape, has at 15 one end a marginal annular rib, the inner face of which provides a convenient location for the matrix of the design.

20 The rib face is so placed that during the casting of the pipe by the centrifugal process, it will receive the impact of the incoming molten metal while the mold is tilted, and the impact of the molten metal displaced longitudinally by centrifugal force during the rotation of the mold, thus to provide a clean cut impression on the casting.

Difficulty has been experienced in obtaining a compact formation of the sand in that part 30 of the core forming the rib. The rib is formed in an annular radial recess between the mold body and the base, and the space is not positioned to receive direct compression stress from a head moving into the mold 35 through the open top.

One of the primary objects of the present invention is the provision of mechanism in connection with a mold of the class described, 40 enabling the compacting of molding sand in a radial direction by a head rotating in the axis of the mold.

Another object is the provision in such a mechanism of normally operative means for 45 maintaining the compressing mechanism in

operative position, released by a selected pressure of the compacted sand.

With these and other objects in view the invention consists in the construction and novel combination of parts fully described 50 hereinafter, illustrated in the accompanying drawings, and pointed out in the claims appended hereto, it being understood that various changes in the form, proportion, size and minor details of construction within the scope 55 of the claims, may be resorted to without departing from the spirit of the invention.

In the drawings forming a part hereof:—

Fig. 1 is a side view of the improved mold with parts in section. 60

Fig. 2 is a plan view.

Fig. 3 is an enlarged plan view of the mold.

Fig. 4 is a vertical section.

Fig. 5 is a section in detail taken substantially on the line 5—5 of Fig. 4. 65

In the present embodiment of the invention a suitable frame is provided comprising an upright 1, a lateral extending table 2 for supporting the mold, and a head 3 for supporting the operating mechanism. The mold is sectional comprising similar sections 6, which are hinged to oppositely disposed standards 7 and 8 extending upwardly from a base plate 9, which seats upon the table 2. The hinged connection between the sections and 70 the standards 7 and 8 is at the tops of the standards, and at the tops of the sections, the hinged connection including pintle pins 10, which engage registering bearings in the standards and bearing lugs 11 on the sections. 80

Mechanism is provided for holding the sections in closed position, including radially extending flanges 12 on the sections, the flanges abutting when the sections are in closed position, and clamps 13 which are pivoted to the standards as indicated at 14. Each 85 of the clamps 13 is fork shaped as shown in Fig. 3, being adapted to engage the abutting flanges at the adjacent side of the mold between the arms of the fork. The body of the 90

fork extends outwardly to facilitate easy disengagement thereof.

A swing plate 15 seats upon the base 9 when the mold parts are assembled for molding. Referring to Fig. 4, it will be seen that the standard 8 has threaded engagement at 16 with the base, and the portion of the standard just above the threaded engagement is cylindrical to fit within the bearing 17 on the swing plate. This connection enables the swing plate to be moved away from over the base.

The upper face of the swing plate is annularly rabbetted as shown at Fig. 4 to provide a central boss 18, which is designed to facilitate the centering of a core plate 19 on the swing plate. This core plate as shown has a central upwardly offset portion 20 which seats over the boss, and in addition has an 20 upstanding annular rib or flange 21 near its peripheral edge. When the mold parts are assembled, as clearly shown in Fig. 4, this rib fits in the lower ends of the sections 6.

Referring to Figs. 3 and 4, it will be seen that the mold parts are so shaped that when assembled in molding position, they will provide for the formation of a core having a substantially cylindrical body indicated at 22, and a marginal rib or flange 23 at one end, the flange being formed between the mold section 6 and the core plate 19. The top of the mold is partially open to enable the formation of an axial scruff pocket in the core. That is, the mold construction enables the molding of a core of the character shown and described in Patent No. 1,613,899, granted on January 11, 1927.

One or both of the mold sections is provided on that part which directly faces the core plate 19 with a design 24^a, in the form of raised characters, which when the core is molded, form depressed characters in the core, this design being in turn reproduced on the casting in raised characters. Because of the location of the design matrix, facing substantially parallel with the axis of the mold, and in the opposite direction from the opening in the top, some difficulty is experienced in so packing the sand in this space as to produce a clear impression of the design on the rib or flange 23.

In the present construction mechanism is provided for compressing the sand in this space, including a strike head 24 pinned or otherwise secured to a spindle 25, which is journaled in the head 3, before mentioned, and is designed to be rotated by means of a crank shaft 26 journaled in the head, and having a bevel gear connection 27 with a jack 28, or countershaft 28, which in turn is geared to the spindle by spur gearing 29. The spindle is slidably mounted in the bearings 30 of the head, and a counterweighted lever 31 pivoted to the upright 1 at 32 is also pivoted to the upper end of the spindle.

The counterweight 33 is normally designed to hold the spindle elevated, and a handled rod 34 is connected with the other end of the spindle to facilitate drawing the same downward when desired. The spindle is sectional as shown in Fig. 1, the upper section 25^a being rotatably connected with the lower section 25, the connection being indicated at 35. The arrangement is such that the strike head may be brought down into the core box or mold as shown in Figs. 1 and 4, through the opening in the top of the mold during the formation of the core, or may be removed therefrom when the mold is opened to remove the core.

A compressing finger 36 is supported by the strike head, the said finger being connected with the lower end of a stem 37 which is mounted to rotate in the strike head on an axis parallel to that of the spindle, and is also mounted for longitudinal movement. The finger, which is of angular formation, is rigid with the lower end of the stem, and a coil spring 38 encircles the stem in the strike head. This spring is arranged about a reduced portion of the stem, being connected with the stem at one end, and with the strike head at the other, and the spring acts normally to hold the stem in the position of Figs. 3 and 4, that is, in elevated position.

The upper end of the stem is provided with a hand piece 39, by means of which it may be moved longitudinally, and rotated with respect to the strike head. The stem is provided with a radial lug or lock pin 40 near its upper end, and the lug is adapted, when the stem is depressed, to register with a plate spring 41 secured to the strike head. This spring is arranged to bear against the outer end of the lug or strike pin 40 when the finger is in working position, and to normally hold the stem with the finger in such position. It will be apparent that when there is stress above a selected point tending to move the finger inward, the lug or lock pin will slip off the spring. The plate spring is, however, engaged by a coil spring 42 arranged in a lateral tubular extension 43 from the strike head. The spring encircles the reduced inner end of an adjusting screw 44 which has threaded engagement with the extension, and which enables tension of the coil spring to be varied. The spring 42 supplements the action of the spring 41, and it is adjusted to yield when the stress on the finger attains a selected degree.

The operation of the device is as follows. With the mold parts assembled, and the striking head lowered into the mold, the stem is pressed downwardly and turned to the right. This operation moves the locking pin 40 into a pocket 45 in the strike head in the inner end of the tubular extension 43, and into position of Fig. 5, with respect to the plate spring 41. A small quantity of sand is then placed in the mold or box, and the spindle is rotated by

means of the crank shaft. The strike head and finger rotate, and the finger presses the sand closely into the space between the facing parts of the core plate and mold body sections. When the pressure of the sand is sufficient to overcome the holding power of the springs against the lock pin, the stem turns and releases the pin 40, and the stem is moved upward by the spring 38. In order to ensure that the element 36 will be in position of Fig. 3 when the strike head is withdrawn from the mold, that is, after the pin 40 is released, a guide 46 is provided in connection with the strike head. This guide is in position to be engaged by the pin 40, when the spring 38 moves the stem upward, and since the guide is inclined, the stem is partially rotated to bring the finger 36 into the position of Figs. 3 and 4, that is, into a position where it will clear the mold.

The strike head is then raised, and the box filled with sand. Again the operator lowers the strike head and rotates the spindle. It will be noted referring to Fig. 4, that the under and outer edge of the strike head are shaped to form the scruff pocket in the core. That is, they have a shape such that when the strike head is rotated the scruff pocket is shaped, while at the same time the sand is compressed into the mold and surplus sand is removed from the core pocket wall. It will be noted that when the head rotates, it is with a neat running fit in the top of the mold. That head is then raised, the clamps loosened, and the mold opened. The sections 6 swing about the pintles 10, providing for vertical movement of the sections with respect to the core plate and to the core, so that there is no marring of the design characters. The swing plate with the core plate and core is then swung out of position above the base and the core removed.

It will be apparent from the construction, that the improved mechanism is adapted for displacing molding sand radially and compressing it in a radial direction, with any construction of mold, and it is of especial advantage in displacing sand and compressing it into recesses in the mold wall. It will be noted from inspection of Fig. 5, that the finger is curved, and that the convex surface thereof engages the sand.

What is claimed as new is:—

1. Mechanism to form a head core having in one end an axial scruff receiving pocket, and at the other an external annular rib, including a mold having an opening in its top of an area corresponding to that of the cross section of the pocket, and a coaxial annular recess at the opposite end to form a rib, means movable through the opening to shape the pocket and to displace molding sand radially and compress it in the recess when said means is rotated with respect to the mold, said means including a strike head

contoured to form the pocket, and a compressing finger normally spring pressed to inoperative position, and set mechanism for holding the finger in operative position and adapted to be released by the pressure of the sand when the selected point of compression is attained. 70

2. Mechanism to form a head core having in one end an axial scruff receiving pocket, and at the other an external annular rib, 75 including a mold having an opening in its top of an area corresponding to that of the cross section of the pocket, and a coaxial annular recess at the opposite end to form the rib, and means movable through the opening to shape the pocket and to displace molding sand radially and compress it in the recess when said means is rotated with respect to the mold, the mold being sectional and including a bottom, and a body composed of similar sections hinged together at the end remote from the bottom to swing outwardly and upwardly away therefrom. 80

3. Mechanism to form a head core having in one end an axial scruff receiving pocket, 85 and at the other an external annular rib, including a mold having an opening in its top of an area corresponding to that of the cross section of the pocket, and a coaxial annular recess at the opposite end to form the rib, and means movable through the opening to shape the pocket and to displace molding sand radially and compress it in the recess when said means is rotated with respect to the mold, the mold being sectional 90 and including a bottom, and a body composed of similar sections hinged together at the end remote from the bottom to swing outwardly and upwardly away therefrom, the annular recess being formed between the bottom and the body sections. 95

4. Mechanism to form a head core having in one end an axial scruff receiving pocket, and at the other an external annular rib, including a mold having an opening in its top of an area corresponding to that of the cross section of the pocket, and a coaxial annular recess at the opposite end to form the rib, and means movable through the opening to shape the pocket and to displace molding sand radially and compress it in the recess when said means is rotated with respect to the mold, the mold being sectional and including a bottom, and a body composed of similar sections hinged together at the end remote from the bottom to swing outwardly and upwardly away therefrom, the annular recess being formed between the bottom and the body sections, the body sections having an annular shoulder between the recess and the body portions thereof, said shoulder facing the bottom and having a design matrix thereon. 100

5. Mechanism to form a head core having in one end an axial scruff receiving pocket, and at the other an external annular rib, in- 105 110 115 120 125 130

cluding a mold having an opening in its top of an area corresponding to that of the cross section of the pocket, and a coaxial annular recess at the opposite end to form the rib, means movable through the opening to shape the pocket and to displace molding sand radially and compress it in the recess when said means is rotated with respect to the mold, said means including a compressing finger normally spring pressed to inoperative position, and set mechanism for holding the finger in operative position, and adapted to be released by excess of pressure on the finger above a selected point.

15 6. Mechanism to form a head core having an annular rib at one end and an axial scruff receiving pocket at the other, including a mold having an opening in its top of an area corresponding to that of the cross section of the pocket, and a coaxial annular recess at the opposite end to form the rib, a strike head movable through the opening and contoured to form the pocket when rotated, said strike head having means to displace molding sand radially and to compress it into the recess.

20 7. In a device of the class described, mechanism to displace molding sand radially and to compress the sand against the wall of a mold, including a rotatable member movable into the mold and provided with a compressing finger normally resiliently held in inoperative position, and set mechanism for holding the finger in operative position adapted to be released by a selected pressure on the finger.

25 8. In a device of the class described, mechanism to displace molding sand radially and to compress the sand against the wall of a mold, including a rotatable member movable into the mold and provided with a compressing finger normally resiliently held in inoperative position, and set mechanism for holding the finger in operative position adapted to be released by a selected pressure on the finger, said finger having a convex surface for engaging the sand.

30 9. In a device of the class described, mechanism to displace molding sand radially and to compress the sand against the wall of a mold, including a rotatable member movable into the mold and provided with a compressing finger normally resiliently held in inoperative position, and set mechanism for holding the finger in operative position adapted to be released by a selected pressure on the finger, means to maintain the finger for rotating and longitudinal movement in the access of the mold, means to rotate the finger, and means to move the finger longitudinally.

35 10. In a device of the class described, mechanism to displace molding sand radially and to compress it against the wall of the mold, including a rotatable member movable into

the mold and provided with a compressing finger normally resiliently held in inoperative position, and mechanism for holding the finger in operative position arranged to be released by pressure on the finger above a selected degree.

Signed at Birmingham, in the county of Jefferson and State of Alabama this 25th day of February, A. D. 1928.
